US0D1010027S

(12) **United States Design Patent** (10) **Patent No.:** **US D1,010,027 S**
(45) **Date of Patent:** **** Jan. 2, 2024**

(54) **SPORTS TRAINING DEVICE**

(71) Applicant: **Global Sports Innovation Ltd.,**
Galashiels (GB)

(72) Inventor: **Richard John Gray**, Galashiels (GB)

(73) Assignee: **GLOBAL SPORTS INNOVATION LTD.**, Galashiels (GB)

(**) Term: **15 Years**

(21) Appl. No.: **29/852,406**

(22) Filed: **Sep. 7, 2022**

Related U.S. Application Data

(62) Division of application No. 29/701,661, filed on Aug. 13, 2019, now Pat. No. Des. 966,445.

(30) **Foreign Application Priority Data**

Feb. 13, 2019 (GB) 6054425
Feb. 13, 2019 (GB) 6054426

(74) *Attorney, Agent, or Firm* — MaxGoLaw PLLC

(57) **CLAIM**

The ornamental design for an sports training device, as shown and described.

DESCRIPTION

FIG. 1 is a perspective view of a sports training device, showing my new design;

FIG. 2 is a front view of the sports training device depicted in FIG. 1;

FIG. 3 is a left side view of the sports training device depicted in FIG. 1;

FIG. 4 is a right side view of the sports training device depicted in FIG. 1;

FIG. 5 is a back view of the sports training device depicted in FIG. 1;

FIG. 6 is a top view of of the sports training device depicted in FIG. 1; and,

FIG. 7 is a bottom view of of the sports training device depicted in FIG. 1.

The broken lines in the drawings depict portions of the sports training device that form no part of the claimed design.

1 Claim, 7 Drawing Sheets
